(57) **CLAIM**

We claim the ornamental design for an ironing board, as shown and described.

DESCRIPTION

FIG. 1 is a perspective view of an ironing board showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the ironing board shown in a state of use;

FIG. 9 is a perspective view of the ironing board showing an alternate configuration with the auxiliary ironing board unfolded;

FIG. 10 is a front elevation view thereof;

FIG. 11 is a rear elevation view thereof;

FIG. 12 is a left-side elevation view thereof;

FIG. 13 is a right-side elevation view thereof;

FIG. 14 is a top plan view thereof;

FIG. 15 is a bottom plan view thereof;

FIG. 16 is a perspective view of the ironing board shown in a state of use;

FIG. 17 is a perspective view of the ironing board showing an alternate configuration with the hanger unfolded;

FIG. 18 is a front elevation view thereof;

FIG. 19 is a rear elevation view thereof;

FIG. 20 is a left-side elevation view thereof;

FIG. 21 is a right-side elevation view thereof;

(Continued)

FIG. 22 is a top plan view thereof;
 FIG. 23 is a bottom plan view thereof; and,
 FIG. 24 is an enlarged perspective view of the rear upper
 portion of the ironing board with the hanger unfolded.
 The broken lines shown in the figures depict portions of the
 ironing board that form no part of the claimed design. The
 rectangular dashed broken line in FIG. 24 shows the bound-
 ary of the enlarged view and forms no part of the claimed
 design.
